UNITED STATES PATENT OFFICE.

CLARA BELL, OF STAFFORD, NEW YORK.

DESIGN FOR A SAFETY-PIN.

SPECIFICATION forming part of Design No. 34,163, dated March 5, 1901.

Application filed February 11, 1901. Serial No. 46,943. Term of patent 14 years.

To all whom it may concern:

Be it known that I, CLARA BELL, a citizen of the United States, residing at Stafford, in the county of Genesee and State of New York, have produced a new and original Design for a Safety-Pin, of which the following is a specification.

This invention relates to a new and original design for a safety-pin, and has for its object to provide a design of this character which shall be both useful and ornamental.

The invention consists in the design for a safety-pin, as hereinafter described, and shown in the accompanying drawings.

In the drawings, Figure 1 is a perspective view of a safety-pin embodying the present design. Fig. 2 is a plan view thereof. Fig. 3 is an end view.

Like characters of reference designate corresponding parts in all of the figures of the drawings.

The present design is characterized by the opposite substantially parallel bar members 1 and 2, respectively, and the hook-shaped member 3, which is projected laterally outward from one member and offset in a plane substantially parallel with that of the bar members. The hook-shaped member has a

shank portion of two substantially parallel members 4, which extend at substantially 30° right angles from the bar member 2 and in the same plane with both bar members. The outer tongue portion of the hook is in the form of a loop 5, which is disposed substantially parallel with the shank portion and has 35 its greatest width at an intermediate point, from which the loop tapers in opposite directions, thereby forming a substantially diamond-shaped loop which is closed at that end which is next to the adjacent bar member 40 and is open at the opposite end thereof, where its sides are bowed around and merge into the respective shank members. Moreover, each member 4 is bowed or arched inwardly toward the diamond-shaped loop. 45

What is claimed is—

The design for a safety-pin substantially as shown and described.

In testimony that I claim the foregoing as my own I have hereto affixed my signature in 50 the presence of two witnesses.

CLARA BELL.
